Specification of Letters Patent.

Patented July 13, 1915.

Application filed April 3, 1913. Serial No. 758,629.

To all whom it may concern:

Be it known that I, FREDERIC H. MASON, a citizen of the United States, residing at Spokane, in the county of Spokane and 5 State of Washington, have invented certain new and useful Improvements in Valves, of which the following is a specification.

My invention pertains to improvements and features of novelty in valves, but relates more particularly to valves of the balanced-fluid pressure-actuated type. Among the various styles of valves in which this invention may, with advantage, be embodied, may be mentioned those in which a prolonged opening of the valve is required by the manipulation of an operating-means having but little movement and actuated for a short interval only. Another type or form 15 of valve mechanism in which may be incorporated these improvements is that in which the movement of the operating or actuating means directly controls and governs the extent of opening of the valve to regulate the flow of fluid. The third form comprises a 20 valve mechanism which can, with facility, be constructed so as to be capable of operation at a distance from the valve proper.

One of the leading objects of the invention is the provision of a valve construction 30 which will work equally well under widely different pressures without requiring the adjustment or regulation of any part of the valve structure. This is of special importance when it is remembered that in the 35 large office buildings of the present day, the water pressure is different on every floor of the building, and if an adjustment or regulation of the valve to meet these different pressures is necessary it occasions much 40 trouble and difficulty in securing the proper adjustment.

Another feature of my improved structure resides in the positive means which prevents leakage of the fluid about or around the 45 stem of the operating-mechanism, which in some instances may be a push-button-construction.

A further object of the invention is the elimination of noise, vibration, water-hammer, or hissing.

It will be observed also that I have been able to incorporate in the various embodiments of this invention many features of simplicity of construction and durability of 55 parts, and that the valve, although it re-

mains open a substantial length of time to secure the proper flushing when it is used for such purpose, has, nevertheless, only a limited movement or travel.

In order that those skilled in this art may have a full and complete understanding of the invention, I have illustrated preferable and desirable embodiments of the same in the accompanying drawings forming a part of this specification and to which reference should be made in connection with the following detailed description of the construction and operation of the parts and elements constituting the various structures.

In these drawings: Figure 1 is a central 70 vertical section through a flushing valve embodying my invention, such valve being adapted to have a retarded closing movement whereby to secure the discharge of fluid during the desired interval of time. 75 In this view the valve is shown in closed position. Fig. 2 is a similar view illustrating the valve in open position; Fig. 3 is a bottom plan view of the main valve, the same being shown on an enlarged scale; Fig. 4 is a top plan view of the main valve with the inner holding-means for the packing-ring removed so as to more clearly show the construction and arrangement of the cleaning-pins for the small ports of the valve; 85 Fig. 5 is a perspective view showing the bottom side of one of the wings of the push-button operating-mechanism; Fig. 6 is a plan view of the structure shown in Fig. 1 with the push-button operating-mechanism 90 and secondary or diaphragm valve removed, a portion of the structure being broken away to more clearly illustrate the means employed for making a fluid-tight connection between the valve-casing and the valve-housing; Fig. 7 is a horizontal section on line 7—7 of Fig. 2, the parts being viewed in the direction indicated by the arrows; Fig. 8 is a central vertical section of a basin-cock embodying the invention; and Fig. 9 100 is a modified valve construction capable of operation at a distance.

Referring to the drawings, more particularly Figs. 1 to 7 inclusive, it will be observed that the construction embodies a 105 valve-housing 20 having at one side an inlet 21 and at its bottom an outlet 22. As is clearly shown, for example in Fig. 1, this valve-housing or inclosing shell is hollow, having an interior chamber 23 of substan- 110

tial capacity. Projecting inwardly of this valve-housing is an annular upstanding flange 24 surrounding the outlet 22, the inner edge of such flange forming a seat for the main valve described hereinafter. The top portion or wall of this housing 20 has a centrally-disposed threaded aperture 25 adapted to receive and accommodate a valve-casing described below. This top wall 10 of the housing 20 has also an enlargement formed by an inner wall or surface 26 and an end-wall 27. Also the top of the housing has an annular channel 28 communicating at the side of the housing opposite the inlet 15 21, with a discharge channel 29 opening at its bottom end into the outlet 22.

The valve-casing referred to above comprises a main body-portion 30 screw-threaded on its exterior so as to be capable of 20 being screwed into the housing 20 by co-operation with the threads 25, as is clearly illustrated. Above the threaded part the casing has a shouldered portion 31 adapted to fit into the enlargement of the valve-housing, and in order to form a fluid tight joint between this portion 31 and the top wall of the housing, I provide the latter with an external circular groove 32 accommodating a ring-packing 33 of any suitable 25 or desirable material, and coöperating with such packing is a sharp edged rib 34, integral with and projecting inwardly from the portion 31 of the valve-casing. As will be readily understood, this rib embeds itself in the 30 packing, to provide the fluid-tight joint referred to. Outwardly of the portion 31 the casing has a substantially flat enlargement 35 adapted to bear against the peripheral or marginal portions of the top flat surface of the housing 20. Upstanding from the part 35 is an integral boss 36, hexagonal externally and screw-threaded on its interior at 37 for the accommodation and retention of a valve-operating mechanism described hereinafter. Extended across the interior of this valve-casing is an integral wall 38 having in its outer face a centrally-disposed round recess or cavity 39 which is made to communicate with the discharge channel 28 by 40 means of a plurality of radially-disposed passages 40. The portion of the wall 38 at the center of the cavity 39 is apertured at 41 to provide a port or opening and is deflected upwardly to form around the port a valve-seat with which a secondary valve referred to below, connects. This casing 30 has a depending or inwardly extended flange or petticoat 42 overlapping for a short distance the upper end of the flange 24, being spaced away therefrom a substantial distance, as indicated in Figs. 1 and 2. The lower end of this flange or petticoat 42 is reduced in thickness and is screw-threaded for the accommodation of a tapered or conically-shaped shell or flange-

extension 43 which constitutes a sleeve, surrounding but spaced away from the flange 24. The interior of this valve-casing 30, which is removably fitted in the valve-housing, constitutes a cylindrical chamber 44 in which snugly but slidingly fits a main valve 45 comprising an enlarged shell-portion 46 outstanding from the main body 47 of the valve, the latter at its inner edge having an inwardly-extended flange 48 acting as holding-means for the valve packing 49, such as rubber, leather, or any other suitable material, and which is adapted, in the closing position of the valve, to rest upon the edge of the flange 24 and close communication between the inlet 21 and the outlet 22. The inner portion of the body 47 of the valve is screw-threaded to receive a similarly threaded packing-retainer 50, which is adapted to be screwed into the body of the valve and bear against the top surface of the packing 49, as is clearly illustrated. At its central portion such retainer has a boss or enlargement 51 with a slot 52 for the application of a screw-driver or similar tool to effect the screwing in of the retainer against the packing. Internally this boss has a screw-threaded recess 53 for the reception of the inner end of the screw-threaded stem of a packing holder or shield 54, provided with an angular head 55 to facilitate its turning and threading into the cavity 53, the packing 49 being apertured at its center for the accommodation of the shank of this holder.

At a plurality of points around the circumference of the main body 47 of the valve, the latter has on its under surface recesses 56, and the top walls of such recesses, which are preferably made comparatively thin, have holes or apertures 57 forming ports for the passage of the fluid from one side to the other of the main valve. Owing to the small size of these ports, it is desirable to supply some means to prevent them from becoming clogged or choked with mud, sand, or the like, and to effect this purpose, I use in each of these holes 57 a small-headed pin 58, which may be like the ordinary pins used for fastening ends of ribbons. In other words, they are common pins of small variety. These pins are prevented from falling down through the apertures or ports in which they fit by means of their heads, and they are also prevented from passing upwardly out of such ports by a circular flange 59 extended laterally outwardly from the top of the packing-retainer 50 and overlying or overlapping the heads of such pins. It will be noticed from the illustration that the retaining flange 59 is located some distance above the heads of the pins so that as the main valve reciprocates in its opening and closing movements, the pins will likewise shift in their ports, acting to dislodge anything tending to their clogging or closing.

In other words, these pins are freely and loosely held in the holes. Owing to the inertia of the pins, and possibly, to the currents in the fluid controlled, these pins have 5 a distinct thrust and movement relative to the main valve, whereby they constitute effective means for keeping these small ports open at all times. It will be noticed that this main valve is considerably larger than 10 the small opening of the sleeve 43, which permits the latter to act not only as means to determine the direction of flow of the fluid in the valve, but also as a retainer to hold the main valve in the casing 30 when 15 the latter is unscrewed from or is being replaced in the valve-housing 20.

The operating-mechanism for the combination diaphragm and secondary valve comprises the following parts and instruments: 20 A flexible combined diaphragm or gasket, and secondary valve 60, which may be made of rubber or other suitable material, has its circular edge-portion held in fluid-tight engagement with the top surface of the 25 wall 38 by means of a screw-threaded fitting 61 screwed into the top of the valve-casing, the lower end of such fitting bearing directly against the edge-portion only of the rubber disk or diaphragm. To limit and 30 restrict the compression of such resilient diaphragm by the fitting 61, the latter is shouldered at 62 to bear against the outer face of the valve casing, and by this means excessive compression of the edge of the 35 diaphragm or cutting of the same is prevented. To facilitate the threading and unthreading of this fitting 61 it is made of hexagonal or other angular shape at 63, whereby the application of a wrench thereto 40 may be effected with facility and ease. This fitting 61 has centrally therein a cylindrical chamber 64 adapted to slidably receive the enlarged piston-portion 65 of a valve-stem 66, the inner enlarged head end 67 of which 45 is molded in the correspondingly enlarged central portion of the rubber secondary valve or diaphragm 60, such rubber under normal conditions bearing against the valve-seat surrounding the port 41, and closing 50 such port, as indicated in Fig. 1. In order to maintain such closure, a spiral spring 68 is interposed between the enlargement 65 of the stem and outer wall 69 of the fitting, the latter being provided with an inwardly extended boss 70 which, together 55 with the end-wall 69, are apertured to form a guiding-bearing for the cylindrical portion 66 of the valve stem. Screwed on the top of this fitting is a hollow push-button holder 71 apertured centrally for the accommodation of a push-button 72 which has along its inner edge a small outstanding flange 73 to prevent its outward passage 60 through the holder or bonnet 71. The outer portion of the fitting 61 and the inner por-

tion of the holder or bonnet 71 are provided with registering cavities forming a chamber 74 containing a pair of substantially semi-circular wings 75, each provided along its straight edge with a semi-circular recess 76 70 adapted to fit around the reduced portion 77 of the stem 66. Each of such wings on its under surface has a fulcrum rib 78, and on its grooved edge opposite recess 76 it has an overturned portion 79, on which the flange 73 75 of the push-button rests.

The operation of this valve, so far as its functions and peculiarities are at present understood, appears to be as follows: Assuming that the valve shown in Figs. 1 to 7 is applied to water-closet structure requiring flushing, and that it is desired to permit the water to pass through this valve for a given period with only a slight movement of the push-button, and without requiring 85 the attendant to maintain pressure on the push-button, but who merely presses inwardly the button 72 and at once releases such pressure. When the bottom moves inwardly in response to such manipulation, 90 the circular flange 73 of the button by engagement with the ribs or outwardly-turned parts 79 of the two wings 75 rocks both of such wings on their fulcrum ribs 78 which rest on the wall of the fitting 61 forming 95 the bottom or inward wall of the cavity 74. Such forward movement of the outer portions of these wings causes an outward movement of the recessed parts 76, which, by encircling the stem 77 of the valve, lift 100 105 or shift such stem outwardly in opposition to the expansive force of the spring 68, the stem being guided in this movement by the coöperation of its enlarged part 65 with the fitting 61 and the stem 66 with the bearing in which it fits. This lifting, or outward movement of the stem causes a flexing of the rubber or other resilient packing or diaphragm 60, as shown in Fig. 2, whereby the valve 41 is opened. This releases the pressure of the fluid on top of the main valve 110 in chamber 44. In other words, it causes an unbalancing of the pressures on the two sides of the main valve, or, stated differently, it reduces the pressure on the top of 115 the valve to less than that on the under side of the valve. The pressure below the main valve, therefore, pushes the latter upwardly rapidly, expelling the water through the port 41, from which it flows into the chamber 39 and through the passage 40 and groove 28 to the discharge passage 29, and into the outlet 22. As soon as the main valve is thus lifted by the water pressure beneath it from its seat on the flange 24, 120 the discharge of water occurs through the outlet 22, the suction of which facilitates and aids in expelling the water from the chamber 44 above the valve. The water in entering the inlet 21 fills the entire chamber 125 130

23 surrounding the valve-casing and sleeve 43, and also the inwardly-projecting outlet flange, and before this water can escape through the outlet its direction of flow is controlled and governed by the arrangement of parts and the shape of the sleeve 43. It will be appreciated, that the water, as it passes upwardly through the sleeve 43 and valve-casing 42, is directed upwardly 10 against the main valve and in order to escape through the outlet 22 is compelled to reverse its direction of travel beneath the main valve. This flow of the water assists in maintaining the main valve away from 15 its seat and therefore, to a considerable extent, retards its closing action. Stated differently, the forward pressure of the water passing into the valve-casing 30 will be concentrated and directed against the valve in 20 opposition to the direction the valve moves in closing. It should be observed that the area of cross-section of the inlet 21 is greater than that of the outlet 22, whereby sufficient and adequate pressure is maintained within 25 the valve-casing to retard the closing of the main valve, as explained above. Also, the fact that the inlet and the chamber 23 entirely surrounding the valve-casing are at 30 the same level as the main valve and its associated parts, assists in the lifting of the main valve and the retarding of its closing, because of the prolonged pressure on its bottom face. Gradually the water passes through the ports or holes 57, and possibly, 35 some of the water passes around the valve so that gradually the liquid accumulates above the main valve and its pressure increases, and after an interval the main valve, due to the greater pressure on its 40 top, is again seated gently on the seat of the discharge flange 24. During this gradual closing travel of the valve, the pressure on its under side increases due to the fact of closing the discharge opening, which action 45 results in a gentle and noiseless seating of the valve. During the opening and closing movement of the main valve, the pins 58 are jarred and move in their ports 57 so that the latter are at all times maintained entirely 50 free from clogging and the possibility of becoming accidentally clogged and inoperative. It should be observed also that there is no packing or screw-threaded connection between the top of the interior of 55 the valve-casing and the other parts of the structure, so that possible leakage at this portion of the device due to high pressure is entirely eliminated. Obviously, the compartment formed by the combined valve-casing and sleeve 43 is divided into two 60 chambers by the main valve, the lower chamber being between the discharge flange 24 and the valve-casing and sleeve referred to, while the upper chamber is entirely within 65 the valve-casing itself. When the valve is

in closed position, the pressure on the top of the valve due to the liquid pressure in the upper chamber and the area exposed is greater than that on the under side of the valve, so that the latter is maintained closed, 70 but when the valve is closing the pressures on its opposite sides are substantially equal or nearly balanced, which results in a slow and easy closing of the valve.

Regarding the secondary valve controlling 75 the port 41, a valuable function is obtained in the arrangement of parts, particularly by using the edge-portion of this secondary valve as a gasket, so that under no circumstances can the water issuing from the port 80 41 leak around the push-button mechanism, because a liquid-tight joint is maintained by means of the diaphragm or rubber valve member 60. Not only is the arrangement of parts effective in securing the functions and 85 operations referred to, but the elements entering into the construction are simple in structure, may be readily taken out and replaced, and are not at all subject or likely 90 to damage or injury.

I wish to have it understood that although the movement of the push-button is extremely slight, possibly not to exceed 1/32 of an inch, and although the time of pushing such button is possibly not more than 95 one second, the water will continue to flow at full capacity through the main valve for a considerable number of seconds, sufficient to obtain a full and complete flushing action such as is desired, and the necessary refill of 100 the siphon bowl.

Although I have indicated above a theory as to the operation of this structure, I do not wish to be bound by such theory, it being presented here merely as an assistance in an understanding of the action of the valve, but I am frank to state that although I am not certain that the theory advanced is the only one or is necessarily the correct one, I am certain because of tests made, 110 that the valve operates in the manner described. In case it is desired, in a construction of this character to control the amount of flow of liquid through the valve and be able to open and close the main valve gradually, that is, without the retarded action above referred to, it is merely necessary to make the port 41 considerably smaller so that the water or other fluid cannot flow therethrough as rapidly as in the construction shown. Under these circumstances, the operator can open the valve any predetermined amount and maintain substantially any predetermined flow as long as he desires by merely holding his thumb on the 115 push-button, and merely holding the latter an amount and period corresponding to the flow desired. In order that such a regulated flow may be more definitely obtained, as for instance, in a basin-cock, I have illustrated 120 125 130

an embodiment of such invention in such a device in Fig. 8. In this case, the form, shape, and contour of the combined nozzle and basin-cock of valve-housing 80 is somewhat different from that of the corresponding part 20 of the valve shown in Fig. 1, but all of the main features are present in both constructions. In the device of Fig. 8 the valve-housing is provided with an inlet 81 and an outlet 82. The other parts of the mechanism are of substantially the same character as those in Fig. 1 with the exception of the secondary valve-operating mechanism, and for that reason I have not deemed it necessary to describe in detail the main valve, the valve-casing, the depending sleeve, the circular flange around the outlet, the water-tight joints, cleaning pins, etc., because these are sufficiently clearly illustrated in Fig. 8 and a minute and precise description of the mechanical features of construction is apparently unnecessary. In this basin-cock I provide an inclined discharge passage 83 corresponding to the passage 29 of the other construction, but in function and operation the parts of this assembled structure are substantially the same as those of the other device. The secondary valve-operating mechanism of this basin-cock comprises a bonnet or shell 84 screw-threaded into the top of the valve-casing, and bearing against the secondary flexible valve 85 which in this instance is of simple modified construction in that it not only has molded in its enlarged central portion the valve stem, but also a cleaning-pin 86 projecting downwardly into the port of the valve casing, which, in this particular embodiment of the invention is desirably smaller than the corresponding port of the retarded closing device of Fig. 1. The stem 87 of the valve whose head is contained within and molded in the rubber 85 has an outer enlarged screw-threaded portion 88 which co-acts with a correspondingly threaded cavity in an operating member or sleeve 89 held from passing outwardly through the central unthreaded opening 90 of the bonnet 84 by an outstanding flange 91. The protruding portion of this member 89 has fastened thereto in any desired manner, a handle 92 which overlaps the bonnet at 93 adjacent to the opening 90, so that by turning this handle the member 89 will be likewise turned and because of the screw-threaded connection between such member and the stem of the valve, the valve itself will be raised or lowered, depending upon the direction of turning of the handle, and the valve will be opened an amount depending upon the extent of the turning of the handle. The operation of this valve is much like that shown in Figs. 1 and 2, but with this particular difference that the operator, instead of merely temporarily actu-

ating the operating-mechanism turns the same the desired amount to obtain the desired flow and the main valve will then float or remain open in a position which is determined by the extent of turning of this handle. The valve will remain open until again closed by the operator. In this case the handle has a positive and direct regulation of the amount of flow as distinguished from a more or less predetermined flow or retarded cessation as in the previous instance.

Each movement of the secondary valve acts to effect a cleaning of the valve-casing port because of the reciprocation of the cleaning-pin positively attached thereto. In this instance the size of the port of the valve-casing in which the cleaning-pin 86 projects is so chosen as to maintain a pressure in the chamber above the valve. In other words, the fluid can flow through the ports of the main valve because of their size, and also around the valve more rapidly than it can flow through the small port of the valve-casing. Because of this, the operator has complete control of the actuation of the valve. It will be appreciated therefore, that the valve will open or move from its seat an amount depending directly upon the extent of turning of the operating-handle, which of course, determines the extent of lifting of the secondary valve.

If it should be desired to make a basin-cock of this general character of the self-closing type, it is simply necessary to substitute the secondary valve-operating push-button mechanism of Fig. 1 for that shown in Fig. 8, and under those circumstances, the person operating the valve has direct control of the amount of flow through the extent to which he thrusts inwardly the push-button. Obviously, the water will continue to flow as long as the push-button is maintained depressed, and will close as soon as the pressure on the button is released. In case it is desired to provide a construction of this general character operable at a distance, this can be readily accomplished, as, for instance, by means of the construction shown in Fig. 9. The valve-housing, valve, and other associated parts are substantially the same as those shown in Fig. 1, with the exception of the valve-casing and the secondary valve. In this case the casing 94 has a flexible diaphragm secondary valve held in position in association with the valve-casing port 96 by means of an apertured fitting 97 binding and holding the edge-portion of the diaphragm in the casing. In this instance the valve casing 94 has secured into its top a dome or shell 98 leading from which is a pressure-pipe 99 fitted at a distance with a push-button valve 100 connected to a drain 101. In order to secure a pressure on the top of the secondary

diaphragm valve 95, that is, a pressure inside of the dome or shell 98, the valve-casing is provided with a plurality of passages 102 extended therethrough so as to connect the chamber 23 with the interior of the casting or shell 98. Owing to the pressure which will be present in the top portion of this valve-construction, a fluid-tight gasket-joint 103 is used between the member 98 and the valve-casing. Under normal circumstances, when the push-button valve 100 is closed, the fluid pressure in the casing 98 is the same as that in the valve-housing 23, because of the communication between these two compartments by the passages 102. Such pressure on top of the secondary valve 95 maintains the same closed on the port 96, which results in the main valve remaining on its seat around the discharge opening, as will be readily understood. When it is desired to have the main valve open, the operator merely pushes the spring-pressed button of the valve 100 so as to release the pressure in the casing 98, the fluid flowing through the exit or discharge-pipe 101 more rapidly than it can enter the chamber 98 through the plurality of passages 102. In this way the pressure in the chamber 98 is reduced sufficiently so that the pressure on the bottom side of the secondary valve 95 will exceed it and cause a lifting of such valve, thereby opening port 96 with a resulting opening of the main valve, as has been explained in connection with the other construction. To close the main valve it is merely necessary to release the pressure on the push button of the valve 100, which closes such valve, the necessary result being that the pressure accumulates in the chamber 98 rapidly causing an excess pressure on top of the valve 95, which closes the same against the port 96; then the main valve descends and rests on its seat. Whether or not this embodiment of the invention as shown in Fig. 9 will act with a retarded closing as in the case of the construction shown in Fig. 1, or whether the operator can directly and instantly govern the amount of flow, depends to a large extent upon the size of the port 96.

While I have herein shown several embodiments of this invention, and have described their structural features rather minutely, I do not wish to have it understood that the invention is limited and restricted to these particular embodiments, because the invention may be incorporated in a large variety of devices and many minor mechanical changes may be made in the structures shown and described, without departure from the substance of the invention and without the sacrifice of any of its substantial benefits and advantages. Above, I have indicated that the valve may be used in con-

nexion with liquid, more particularly water, but it is also capable of employment in connection with other liquids and fluids such as gas, steam, compressed air, and the like.

I claim:

1. In a valve, the combination of a hollow valve-housing having an inlet thereto and an outlet therefrom, said outlet being surrounded by an inwardly-extended flange, a ported valve-casing projecting into the hollow interior of said valve-housing and telescoping over and spaced away from said flange and also spaced away from the wall of said housing, a valve slidable in said casing adapted by co-operation with said outlet flange to establish and break communication between said inlet and outlet; the construction having means to permit fluid to pass from one side of the valve to the other, a secondary valve controlling the port of said valve-casing, and means to actuate said secondary valve, whereby the fluid in passing from the inlet to the outlet through the housing and the space between said flange and valve-casing strikes against the main valve in a direction substantially the same as the opening travel of said valve, substantially as described.

2. In a valve, the combination of a hollow valve-housing having an inlet thereto and an outlet therefrom, said outlet being surrounded by an inwardly-projecting flange, a ported valve-casing fitted in said housing and projecting into the hollow interior of said valve-housing, said projecting-portion telescoping over and spaced away from said flange and also spaced away from the wall of said housing, a sleeve on said projecting-portion of the valve-casing, said sleeve also telescoping over and spaced away from said flange, said sleeve comprising an inward extension of the valve-casing, a valve slidable in said casing and adapted by co-operation with said outlet flange to establish and break communication between said inlet and outlet, the construction having means to permit fluid to pass from one side of the valve to the other, a secondary valve co-operating with the port of said casing, and means to operate said secondary valve, whereby the fluid in passing from the inlet to the outlet through the housing and the space between said flange, sleeve, and valve-casing, is caused to strike the valve in a direction substantially the same as that of the opening travel of the valve, substantially as described.

3. In a valve, the combination of a hollow valve-housing having an inlet thereto and an outlet therefrom, said outlet being surrounded by an inwardly-projecting flange, a ported valve-casing removably fitted in said valve-housing and having a portion projecting into the hollow interior of said valve-housing, said projecting-portion being

spaced away from the valve-housing wall, said projecting-portion telescoping with and spaced away from said flange, a sleeve having a tapered inner chamber removably fitted on 5 and forming an extension of said inwardly-projecting portion of the valve-casing, said sleeve encircling and spaced away from said flange, a valve slidable in said casing and adapted by coöperation with said outlet 10 flange to establish and break communication between said inlet and outlet, the construction having means to permit the fluid to pass from one side of the valve to the other, a secondary valve coöperating with the port 15 of said valve-casing, and means for operating said secondary valve, whereby the fluid in passing from the inlet to the outlet through the space between said flange, sleeve, and valve-casing, is caused to strike 20 the valve in a direction substantially the same as that of the opening travel of the valve, said sleeve not only assisting in governing the direction of flow of the fluid, but also acting as a removable retainer to maintain 25 the main valve in the valve-casing, substantially as described.

4. In a valve, the combination of a hollow valve housing having an inlet thereto and an outlet therefrom, said outlet being surrounded 30 by an inwardly-extended flange, a ported valve casing projecting into the hollow interior of said valve-housing and telescoping over and spaced away from said flange and also spaced away from the wall of said housing, a valve slidable in said casing adapted 35 by coöperation with said outlet-flange to establish and break communication between said inlet and outlet, the construction having means to permit fluid to pass from one 40 side of the valve to the other, a secondary valve controlling the port of said valve-casing, a fixed bonnet or cap, a member having a rotatable bearing in said bonnet but held 45 from longitudinal movement, a valve-stem associated with said secondary valve, and a

screw-threaded connection between said rotatable member and stem whereby turning of said member shifts the valve-stem lengthwise, the fluid in passing from the inlet to the outlet through the housing and the space 50 between said flange and valve-casing striking against the main-valve in a direction substantially the same as that of the opening travel of said valve, substantially as described. 55

5. In a valve, the combination of a hollow valve-housing having an inlet thereto and an outlet therefrom, said outlet being surrounded by an inwardly-projecting flange, a ported valve-casing removably fitted in 60 said valve-housing and having a portion projecting into the hollow interior of said housing, said projecting portion being spaced away from the inner-wall of said housing and telescoping with and spaced away from said 65 outlet flange, a valve slidable in said casing and adapted by coöperation with said flange to establish and break communication between 70 said inlet and outlet, whereby the fluid in passing from the inlet to the outlet 70 through the housing and the space between said flange and projecting-portion of the valve-casing is caused to strike against the valve in a direction substantially the same as that of the opening travel of the valve, a 75 flexible rubber secondary valve coöperating with the port of said casing, a valve-stem having a portion molded in said rubber, a fixed bonnet or cap, a member rotatable in a bearing of said bonnet but held against longitudinal movement, and a threaded connection between said rotatable member and the valve-stem whereby turning of the rotatable member shifts the valve-stem longitudinally and flexes the valve toward and away from 85 said port, substantially as described.
